(57) **CLAIM**

The ornamental design for a bottle, as shown and described.

DESCRIPTION

FIG. 1 is a right, front, upper perspective view of a bottle embodying our new design;

FIG. 2 is a front elevational view thereof, the rear elevational view being a mirror image of the front elevational view shown;

FIG. 3 is a right side elevational view thereof;

FIG. 4 is a left side elevational view thereof;

FIG. 5 is a top plan view thereof; and,

FIG. 6 is a bottom plan view thereof.

The dotted line representations of a top outlet in FIGS. 1-5, of ribs in FIGS. 1, 2, 4, and 5, of a button in FIGS. 1, 3, and 4, and of bottom structure in FIG. 6, are for illustrative purposes only and form no part of the claimed design.
